UNITED STATES PATENT OFFICE

2,597,937

PUMP BARREL CLEANING APPARATUS

Frank Krizman and Charles Jonette, Dawson,
Yukon Territory, Canada

Application February 28, 1947, Serial No. 731,686

1 Claim. (Cl. 214—1)

1

The present invention relates to means whereby drill pump barrels can be cleaned of mud and other foreign matter, the principal object being to provide a tiltable seat for receiving the pump barrel when extracted from a well, thus supporting the weight of the barrel and permitting it to be tilted over into a trough and to a position whereby the interior of the barrel can be thoroughly washed.

Another object of the invention is to provide an attachment for wells constructed and arranged to permit easy handling of a well extracted pump barrel, especially during the operation of cleaning the same, thus minimizing to a considerable extent the utilization of manual effort.

A further object of the invention is to provide a device of the character stated which can be easily installed on the usual drill frame and conveniently used whenever the occasion demands.

Still a further object of the invention is to provide a drill pump barrel manipulating device of the character stated, which is of simple construction and capable of being installed at low cost.

These and various other objects and advantages of the invention will become apparent to the reader of the following description.

In the drawings:

Figure 1 is a fragmentary side elevational view showing a pump barrel as it has been lowered into a cleaning trough.

Figure 2 is a fragmentary vertical sectional view showing the barrel receiving cup and drill frame attaching means.

Figure 3 is a top plan view of the structure shown in Figure 2 with parts in section.

Figure 4 is a fragmentary vertical sectional view taken on line 4—4 of Figure 3.

Referring to the drawings, reference character A denotes a pump barrel cleaning trough which has a bottom and side wall and into this trough, for the purpose of cleaning, is lowered the usual pump structure B which includes a barrel C and pump rod D, to which the usual pump line E is connected and which is used in lowering the pump from the well as well as replacing the same.

In carrying out the present invention, a cup generally referred to by numeral 5 is employed and has an inturned flange 6 at its bottom, leaving a substantial opening in the bottom through which the interior of the pump barrel C, when it is seated in the cup, can be flushed.

A U-shaped strap 7 has its medial portion dis-

posed across the open bottom of the cup 5, while its leg portions are secured by rivets or the like 1a to the side of the cup. The legs of the U-shaped strap 7 have outwardly disposed trunnions 8 which project through bearing eyes 9, each eye forming part of a supporting bracket generally referred to by numeral 10. Each of these brackets further consist of an arm 11 projecting from the eye 9 and having a laterally disposed eye 12 for disposition against the corresponding side of the usual drill frame generally referred to by reference character F.

Each bracket eye 9 also has an elongated suspending rod 13 projecting therefrom in diverged relation with respect to the corresponding arm 11 and each of these rods 13 has a hook 14 at its upper end for engagement over the upper edge of the corresponding wall of the frame F.

Bolts, rivets or the like 15 can be disposed through the eyes 12 to secure the arms 13 firmly to the frame F.

The purpose in having the hooks 14 is so that in initially assembling the cup to the drill frame F, the hooks 14 are disposed over the upper edge 25 of the frame F, while the eyes 12 bear against the wall of the frame F in proper position with respect to openings therethrough so that the bolts 15 can be easily set and secured in place. This permits the cup to be placed and secured in 30 position by one man.

On the ends of the trunnions 8 are located stop collars 16, which serve to limit horizontal play of the cup 5.

In the use and operation of the structure described, the pump is first lifted from the well by 35 the usual drill motor and cable and lowered by this power means until the lower end of the pump barrel seats in the cup 5, which is first set in a vertical position, inclining toward the 40 frame F.

When the cup 5 has thus received the pump barrel and is supporting its weight, the attendant, can then swing the barrel and cup outwardly, as slack is allowed on the cable E, until 45 the barrel assumes the position as shown in Figure 1. The pump rod and plunger are now extracted from the pump barrel, so that all mud and other foreign matter in the barrel can be thoroughly washed out into the trough A, after 50 which the plunger and rod are reinserted and the pump is now ready to be tilted upward and subsequently lifted by the drill motor and cable to a position whereby it can be lowered again into the well.

The provision of the above attachment mini-

mizes considerably the amount of labor necessary in cleaning pump barrels, several men being needed heretofore in order to handle the pump, which is usually of heavy weight.

While the foregoing description sets forth the invention in specific terms, it is to be understood that numerous changes in the shape, size and materials may be resorted to without departing from the spirit and scope of the invention as claimed hereinafter.

Having described the invention, what is claimed as new is:

A pump barrel handling apparatus for pumping wells comprising a supporting structure, a bracket extending from the supporting structure, a pump barrel receiving cup swingable on the bracket and adapted to be tilted with a pump barrel therein to dispose the pump barrel to a tilted position for cleaning the interior thereof, said cup having an open bottom provided with an inturned flange for supporting said pump barrel, and said bracket consisting of a pair of arms projecting horizontally from the supporting structure and provided with bearings at the cutter ends thereof, said cup being provided with trunnions disposed in said bearings, each of said bearings having affixed thereto an upwardly and

angularly extending arm, a hook at its free end for disposition over the supporting structure for bracing said horizontal arms and preliminarily supporting the horizontal arms and cup when securing the horizontal arms to the supporting structure.
